UNITED STATES PATENT OFFICE.

EMMIT G. LATTA, OF FRIENDSHIP, NEW YORK, ASSIGNOR OF ONE-HALF
TO ADRIAN C. LATTA, OF SAME PLACE.

VELOCIPED.

SPECIFICATION forming part of Letters Patent No. 326,752, dated September 22, 1885.

Application filed March 5, 1885. (No model.)

To all whom it may concern:

Be it known that I, EMMIT G. LATTA, of Friendship, in the county of Allegany and State of New York, have invented new and 5 useful Improvements in Velocipedes, of which the following is a specification.

This invention relates to an improvement in the steering-head and handle-bar, in the attachment of the handle-bar to the steering-head, and in the construction of the brake-lever and its attachment to the handle-bar, whereby various advantageous results are obtained.

In the accompanying drawings, Figure 1 is a fragmentary sectional elevation of my improved steering-head and handle-bar. Fig. 2 is a top plan view of the same. Fig. 3 is a front elevation of a portion of the handle-bar to which the brake-lever is attached. Fig. 4 is a longitudinal sectional elevation, on an enlarged scale, of the handle-bar lug and connecting parts. Fig. 5 is a similar view showing a modified construction of the handle-bar lug. Fig. 6 is a cross-section, on an enlarged scale, in line $x x$, Fig. 1. Figs. 7, 8, and 9 are cross-sections, on an enlarged scale, in lines $x x$, $y y$, and $z z$, Fig. 2, respectively. Fig. 10 is a perspective view of a portion of the brake-lever fastening. Fig. 11 is a longitudinal section, on an enlarged scale, of the handle-fastening, and Fig. 12 is a cross-section of the same.

Like letters of reference refer to like parts in the several figures.

A represents the steering-head, and a the handle-bar lug formed on the upper front portion of the steering-head.

B is a removable cap or section forming a continuation of the handle-bar lug and applied to the front side of the handle-bar lug, as represented in Fig. 4, or seated in an opening in the lower side of the handle-bar lug, as represented in Fig. 5, so as to form with the handle-bar lug a cylindrical socket which 45 incloses the central portion of the handle-bar C.

c represents a pin secured in the cylindrical portion of the handle-bar C, or a projection formed on the same, and c' represents one or 50 more openings or recesses in the removable

portion B of the handle-bar lug in which the pin c engages, and whereby the handle-bar is rigidly held in position. The pin c is preferably arranged on one side of the plane of the bent portion of the handle-bar, and the opening c' , if but one opening is used, is arranged out of center, so that if it is desired to adjust the bent ends of the handle-bar backwardly or forwardly it may be done by reversing the bar C in the handle-bar lug end for end, or 60 by reversing the cap B, or by reversing both the bar and the cap, whereby a variety of positions of the handle-bar are secured. When a number of openings c' are formed, as represented in the drawings, the position of the 65 handle-bar can be adjusted or changed by the pin c from one of the openings to another, or by reversing the handle-bar or the cap B, or both. Both end portions of the handle-bar lug a and cap B, which extend laterally beyond the steering-head, are provided with tapering screw-threads $d d$, to which are applied tapering screw-nuts D, by which the cap B is firmly drawn against the handle-bar, thereby clamping the same firmly in the handle-bar lug. The bar C is preferably made 70 slightly larger than the opening between the cap and the handle-bar lug a to give the cap the necessary draft. The screw-nuts will hold the handle-bar securely in the lug under the ordinary circumstances, and the pin c and opening c' constitute an additional safeguard against accidental displacement of the handle-bar. The screw-nuts D do not 75 touch the handle-bar outside of the lug, 80 whereby they are enabled to securely clamp the bar in the lug, and whereby the nuts are prevented from being split when a sudden strain is applied to the bar. The tapering form of the ends of the lug and the 85 nuts D prevents the lug from breaking off at the end of the nut, which would be liable to occur if the lug were threaded to fit a nut of uniform diameter. The removable portion of the handle-bar lug is preferably arranged as far as possible on the under side 90 of the lug, to improve the appearance of the lug and to enable the solid part of the lug to better resist the strains to which it is subjected. 95

The lug constructed as above described is 100

equally desirable for straight handle-bars, and will hold a bar made in two parts with their ends screwed or butted together.

In the drawings the handle-bar is shown as being partly hollow and composed of a solid central portion, e , which is clamped in the handle-bar lug end portions, e' , to which the handles E are secured, and hollow intermediate portions, e^2 , which connect the solid end portions with the central portion. The hollow portions e^2 are secured to the solid central portion e just outside the handle bar lug, whereby the same lug is adapted to receive either a solid bar or a hollow bar of the construction shown. The solid and hollow portions of the handle-bar are bent to the proper form and then rigidly secured together by brazing or riveting. By unscrewing the nuts D the cap B and handle-bar can be removed from the steering-head when it is required to pack the machine for shipment, or when a bar of a different form or length is to be put in its place.

F represents the clamp or bracket whereby the brake-lever G is attached to the handle-bar C . The clamp F is secured to the handle-bar by a vertical bolt, f , which also serves as a pivot for the brake-lever. The clamp is constructed of spring sheet metal, and embraces the upper, lower, and rear portions of the handle-bar, and is provided on the front side of the handle-bar with two forwardly-projecting jaws, between which the brake-lever is arranged. The jaws of the clamp are provided on one side of the pivot-bolt f with lips g , which overlap the front side of the brake-lever, and on the other side of the bolt f with lips g' , which overlap the rear side of the brake-lever. These lips form springs which resist the movement of the brake-lever on its pivot and hold the brake-lever in its proper position when not in use. The front and rear sides of the brake-lever are preferably rounded off at its corners between the lips g g' , to facilitate the working of the same. When the outer end of the brake-lever is drawn back in applying the brake, the springs g g' open slightly and permit the rounded portions of the lever to pass between them, and the springs press against these rounded edges of the lever with sufficient force to return the lever to its position of rest when it is released. The rounded ends of the lips of the springs g g' , resting against the flat edges of the brake-lever in its position of rest, require a little extra power to start the brake-lever when applying the brake, but after the rounded parts of the lever have passed between the springs the lever moves easily. By this means the lever and brake are held securely in position when not in use, although a lamp or bell may be attached to the brake, and the nice application of the brake is not interfered with by a stiff spring.

65 The flexible clamp is readily applied to a bent handle-bar after the handles are secured thereto, while ordinary stiff brackets have to

be applied from the end of the handle-bar before the bar is bent.

H represents a stay-piece arranged between the jaws of the clamp F , on the front side of the handle-bar, and composed of two jaws, h h' , resting against the inner sides of the jaws of the clamp, and a connecting curved back plate, h' , which rests against the front side of the handle-bar. This stay-piece may be bent of sheet metal, as represented in Fig. 10, or it may be constructed of cast or other suitable metal. At the junction of the jaws h and the back plate, h' , there are formed stiffening-edges h^2 , which project into the angles between the jaws of the bracket and handle-bar and support the jaws of the bracket, thereby preventing the pivot-bolt from tightening the jaws to such an extent as to interfere with the free movements of the brake-lever.

h^3 is an opening formed in the back plate of the stay-piece H for the accommodation of the rearwardly-projecting hub or curved portion of the brake-lever.

I represents a screw-nut applied to the lower end of the pivot-bolt f , and provided with a tubular extension, i , which surrounds the pivot-bolt and forms a journal on which the brake-lever turns. The upper end of the sleeve i' bears against the upper jaw h of the stay-piece H , and forms a stay which prevents the jaws of the stay-piece H from being pressed against the brake-lever with sufficient force to impair its freedom of movement. The brake-lever and bracket can be removed from the handle-bar by removing the single screw f , and without disturbing the handle, when it is desired to remove the brake from the machine.

The handle-bar is not disfigured by a set-screw which holds the brake in place, and the whole construction is more compact and stronger than the construction heretofore in use.

j represents the tang formed at the outer end of the solid end portion e' , of the handle-bar, and provided with an external screw-thread which is adapted to receive the ordinary pear-shaped handle. Instead of forming this tang on the solid portion e' , it may be formed by threading the outer small end of the tubular portion e^2 .

J is a tube or sleeve provided with an internal screw-thread, so that it can be screwed upon the tang j , and having at its outer end a conical head, k , which is provided with a slot in which a screw-driver can be inserted for applying or removing the tube J .

l represents a sleeve which is fitted on the outer portion of the tube J , and provided at its outer end with a flaring bore which fits the conical head of the tube J . The inner flanged end of the sleeve l is provided with depressions l' , in which a wrench can be inserted for turning the sleeve. The latter is preferably split lengthwise on one side, so that the sleeve can be expanded by screwing it against the conical head k .

m represents a bushing secured in the han-

dle E, and provided with an internal thread which receives the threaded sleeve l. This bushing is preferably employed when the handle is constructed of wood; but when horn or 5 other tough material is employed the screw-thread may be formed in the handle and the bushing may be omitted.

In order to attach the handle to the handle-bar, the sleeve l is first slipped over the tube 10 J, and the latter is firmly screwed upon the tang j, so that it will not turn thereon when in use. The handle E is then placed over the tube J and the sleeve l is screwed into the handle until it bears against the outer end of the 15 tube J, whereby the handle is attached to the handle-bar and at the same time permitted to turn with the sleeve on the tube J.

If it is desired to secure the handle rigidly to the handle-bar, the sleeve l is tightened 20 against the outer conical head, k, of the tube J, whereby the split sleeve l is spread and caused to firmly lock the handle on the handle-bar. This construction admits of the use of the oblong cross-handle or the pear-shaped 25 handle, and the former may be attached rigidly or loosely on the handle-bar, as may be desired. By employing a longer tube, J, the oblong handle may be arranged farther from the steering-head, thereby virtually lengthening 30 the handle-bar. In either case the handle is made in one piece, and is free from projections which would interfere with its convenient use. The long tang for the pear-shaped handle is covered by the tube J, which forms 35 a continuation of the handle-bar to the handle and greatly improves the appearance of the handle-bar.

I am aware that it is not new to support the 40 brake-lever on a pivotal bearing attached to the handle-bar, and I do not broadly claim such construction.

I claim as my invention—

1. The combination, with a handle-bar lug 45 provided with an opening through which the handle-bar is inserted laterally, of a removable cap closing said opening, and fastenings whereby the lug and cap are secured together, substantially as set forth.

2. The combination, with a handle-bar lug 50 and removable cap, both constructed with tapering screw-threaded ends, of tapering screw-nuts applied to said ends, substantially as set forth.

3. The combination, with the handle-bar lug 55 and handle-bar, of a projection and a series of openings formed in the contiguous portions of said parts for rigidly securing the handle-bar in one of a number of different positions, at desire, substantially as set forth.

60 4. The combination, with the handle-bar lug, of a removable cap provided with an opening, e', and a handle-bar provided with a projection, e, substantially as set forth.

5. In a handle-bar, the combination of a 65 solid central portion, e, and tubular portions e', secured to the outer ends of the central portion, e, substantially as set forth.

6. A handle-bar composed of a solid portion, e, solid end portions, e', provided with threaded tangs j, and intermediate tubular portions, e'', substantially as set forth. 70

7. The combination, with the handle-bar and brake-lever, of a flexible sheet-metal clamp embracing the handle-bar and brake-lever, and constructed with two jaws which 75 can be passed over the handle-bar, and a screw or bolt whereby the clamp is tightened on the handle-bar, and which forms a pivotal support for the brake-lever, substantially as set forth. 80

8. The combination, with the handle-bar and brake-lever, of a flexible sheet-metal clamp which embraces the handle-bar and brake-lever, and forms a retaining-spring for the brake-lever and a pivotal support for the 85 same, substantially as set forth.

9. The combination, with the brake-lever and its pivotal support, of springs bearing against the brake-lever on opposite sides of its pivot and tending to return the lever to 90 its position of rest, substantially as set forth.

10. The combination, with the brake-lever and its pivot f, of a supporting-bracket, F, constructed with springs g g', overlapping, respectively, the front and rear edges of the 95 brake-lever, substantially as set forth.

11. The combination, with the handle-bar and brake-lever, of the clamp F, bolt f, and a stay-piece, H, arranged between the jaws of the clamp, substantially as set forth. 100

12. The combination, with the handle-bar and brake lever, of the clamp F, bolt f, and stay-piece H, composed of jaws h, and a back plate, h', provided with ribs or ledges h'', substantially as set forth. 105

13. The combination, with the handle-bar and brake-lever, of the clamp F, bolt f, stay-piece H, and nut I, provided with the tubular extension i', substantially as set forth.

14. The combination, with the handle and handle-bar, of a screw-threaded tang, j, and a tube, J, inclosing the tang and forming a smooth bearing or support for the handle, substantially as set forth. 110

15. The combination, with the internally-threaded handle and the handle-bar, of a screw-threaded tang, j, a tube, J, inclosing the tang and provided with a head at its outer end, and a screw-threaded sleeve, l, substantially as set forth. 115

16. The combination, with the internally-threaded handle and the handle-bar, of a screw-threaded tang, j, a tube, J, inclosing the tang and provided with a conical head, k, at its outer end, and a screw-threaded split sleeve, l, substantially as set forth. 120

Witness my hand this 26th day of February, 1885.

EMMIT G. LATTA.
